UNITED STATES PATENT OFFICE.

WILLIAM HAWDON, OF MIDDLESBROUGH-ON-TEES, ENGLAND.

APPARATUS FOR REMOVING SLAG FROM FURNACES.

SPECIFICATION forming part of Letters Patent No. 447,683, dated March 3, 1891.

Application filed November 5, 1888. Serial No. 290,037. (No model.) Patented in England October 31, 1887, No. 14,803, and in Belgium November 5, 1888, No. 88,846.

To all whom it may concern:

Be it known that I, WILLIAM HAWDON, engineer, a subject of the Queen of Great Britain, residing at the Newlands, Middlesbrough-on-Tees, in the county of York, England, have invented new and useful Improvements in Apparatus for Removing Slag from Furnaces, (for which I have obtained a patent in Great Britain, No. 14,803, bearing date October 31, 1887, and in Belgium, No. 88,846, dated November 5, 1888,) of which the following is a specification.

My said invention relates to improvements in apparatus for removing molten slag, scoria, and other similar materials from furnaces, and after the same have been withdrawn cooling them and depositing them into trucks or other receptacles, by means of which improvements the desired object is effected in an economical, speedy, and convenient manner.

The apparatus, to the construction and arrangement of which this invention relates, consists of one or more endless bands or belts of wire, rope, iron, or steel links or other suitable contrivances, which bands or belts pass or work over two or more series of pulleys, wheels, or drums, to one of which series a rotary motion is given by means of an engine or other prime mover. Attached to the outer face of the said bands or belts is a continuous succession of pans, molds, shapes, or flat plates with upstanding side edges for the reception of the molten material. The said pans, molds, shapes, or plates which are formed of any suitable material, preferably cast-iron, are by preference made in more than one piece or section, the pieces or sections to prevent injury from expansion or contraction being fitted together, as will be well understood by reference to the accompanying drawings. The

before-mentioned endless bands or belts are so arranged that when traveling the upper portion thereof will, after the pans, molds, shapes, or plates have received the molten material, dip into a reservoir of water, taking with it the said pans, molds, shapes, or plates, whereby the latter and their contents are cooled on their journey to the series of pulleys, wheels, or drums at the delivery end.

The said reservoir is supplied with a continuous flow of water, and this is by preference

obtained from a perforated pipe arranged above it, from which pipe the water flows in a series of jets onto the upper faces of the pans, molds, shapes, or plates and the contents thereof, and thence into the reservoir, suitable channels being provided for the escape of the overflow.

I will now proceed to refer to the accompanying drawings, from which the nature of my said invention will be more clearly understood.

The same letters of reference indicate like parts in all the figures.

Figure 1 is a longitudinal view of an apparatus constructed and arranged in accordance with this invention. Figs. 1^a and 1^b show the gearing for adjusting the distance between the pulley-wheels. Fig. 2 is a transverse section of one form of pan, mold, or shape. Figs. 3 and 4 are respectively longitudinal section and top views of three pans, molds, or shapes secured in position on the bands or belts, which are shown in this instance as composed of links. Figs. 5 and 6 are top views of detached pans, molds, or shapes. Figs. 7 and 8 show modifications of the arrangements shown in Figs. 3, 4, 5, and 6, and in which flat plates are substituted for the hollow pans.

A A are the endless bands or belts.

C is a series of pulleys, wheels, or drums, over which one bend or loop of each endless band or belt passes, and the shaft of the said series of pulleys, wheels, or drums is driven through the medium of the driving-shaft B.

E is a series of pulleys, wheels, or drums, over which the other bend or loop of each endless band or belt passes.

D is a water-reservoir, which is shown in section.

F is a channel or runner, through which the molten slag, scoria, or other materials flow and thence fall into the pans, molds, or shapes I, which are fixed on the endless bands or belts A, and are each provided at one side with a lateral flange or projection I², which overlaps the edge or rim of the adjacent side of the next pan, and thus prevents the slag from running between the ends of the pans as they pass under the channel F.

F' is a receptacle, into which the cooled ma-

terial is discharged from the said pans, molds, or shapes as the bands or belts travel round the series of pulleys or wheels E.

5 G are rollers or pulleys, serving as guides and carriers for the lower portion of the bands or belts.

H are perforated pipes, from which water issues to assist in cooling the material, and one of which provides a continuous supply to 10 the reservoir D.

The bearings of the shaft of the series of pulleys, wheels, or drums E are connected to one end of the rods or links N, which are attached or connected at one end to the screw 15 M, which passes through a screw-nut fixed in the worm-wheel L. This wheel gears into a worm, which is fixed on the shaft J, mounted on a bracket. The said screw-nut and worm-wheel L are arranged on the screw M, which 20 passes through the said bracket. By turning the shaft and worm J, and thereby actuating the worm-wheel L, the axle of the shaft of the pulleys, wheels, or drums E is caused to slide one way or the other in suitable 25 bearings, whereby the distance between the two series of pulleys, wheels, or drums C and E is lengthened or shortened, as required. This admits of the easy adjustment of the bands or belts.

30 The arrangement of mechanism, which is illustrated by Figs. 1^a and 1^b, will be found convenient for effecting the desired object; but it is not intended to restrict this invention to the use of the same, as many other 35 simple mechanical arrangements will be found suitable for the purpose.

An essential feature of my invention is that the pans, molds, or shapes are in some cases made in more than one piece or section, 40 inasmuch as I have found that if the pans are made in one piece they are liable to warp and crack with the heat; whereas if they are composed of several pieces there is not the same liability to destruction.

45 Fig. 2 is a transverse section of one form of pan, mold, or shape which is suitable for the purpose of this invention, and which is composed of sections secured together by suitable bolts or rivets passing through the ears 50 or lugs I'.

Figs. 3 and 4 are respectively longitudinal section and top view of three pans, molds, or shapes secured in position on the bands or belts, which are here shown composed of 55 links. Figs. 5 and 6 are top views of detached pans, molds, or shapes, Fig. 5 showing a pan composed of four sections, while Fig. 6 shows a pan composed of but two sections.

In Figs. 7 and 8 a modification of the above 60 arrangement is shown, in which flat plates

are substituted for hollow pans, and when the same are employed the melted slag, after it is cooled, forms a continuous cake or band on the plates, which breaks up into pieces as the plates pass over the pulleys E, each of 65 said plates having a flange or rabbet I², upon which rests the adjacent end of the next plate in order to insure close joints.

The action of the apparatus is as follows: The endless bands or belts A are caused to 70 travel in the direction indicated by the arrow a, and at a portion of their journey they are arranged to dip with the pans, molds, or shapes, which have been filled or partially filled with the molten slag, scoria, or other 75 material flowing from the channel or runner F into the reservoir D, whereby the said pans, molds, or shapes and the contents thereof are cooled as the bands or belts pass over the series of pulleys, wheels, or drums E. The pans, 80 molds, or shapes are tilted and turned over and the contents thereof discharged or delivered into the receptacle F'.

What I claim is—

1. The combination, with the endless carrier or conveyer, of a number of pans secured thereto, each pan being divided into two or more sections and the several sections of each pan being rigidly riveted or bolted together, whereby the said pans may expand and contract under changes of temperature without fracturing, substantially as set forth. 90

2. The combination, with the carrier or conveyer, of pans or molds for the reception of the molten metal, secured thereto, and each 95 being divided longitudinally and transversely and the sections secured rigidly together, substantially as set forth.

3. The combination, with the carrier or conveyer, of pans or molds for the reception of 100 molten metal, each being completely divided longitudinally and transversely and the sections thereof having the ears or flanges I' at intervals along the joints riveted together, substantially as and for the purposes set 105 forth.

4. The combination, with the endless carrier, of a water-trough, pulleys arranged to guide said carrier through said trough, molds or pans secured to said carrier, and a spray-pipe arranged lengthwise of said carrier and adapted to discharge into said pans or molds, substantially as set forth. 110

WILLIAM HAWDON.
